VIDEOTELEPHONE TRANSCEIVER CONTROL UNIT

Henry Dreyfuss, South Pasadena, Calif., and Rembert R. Stokes, Middletown, N.J., assignors to Bell Telephone Laboratories, Incorporated, Murray Hill, N.J., a corporation of New York

Filed Nov. 24, 1967, Ser. No. 9,549

Term of patent 14 years

Int. Cl. D14—03

U.S. Cl. D26—14

FIG. 1

FIG. 2

FIG. 3

FIG. 1 is a left front perspective view of a video-telephone transceiver control unit showing our new design;

FIG. 2 is a right rear perspective view of the video-telephone transceiver control unit shown in FIG. 1; and

FIG. 3 is a left rear perspective view of the video-telephone transceiver control unit shown in FIG. 1.

The dominant features of the design are shown in full lines.

We claim:

The design for a videotelphone transceiver control unit, substantially as shown and described.
